UNITED STATES PATENT OFFICE

RICHARD D. COGSWELL, OF MILLBOURNE, PENNSYLVANIA

BURIAL VAULT

Application filed April 2, 1930. Serial No. 440,926.

This invention relates to burial vaults, and has more particular reference to box-like burial vaults of concrete comprising bottom and lid components with linings of sheet metal.

The main objects of my invention are to insure, in connection with a vault of the specific type referred to, perfect bonding as between the metallic linings and the concrete of the bottom and lid components; and to predetermine, incident to placement of the lid component on the bottom component after lowering of the burial casket at the time of interment, hermetic sealing of the vault without necessitating the aid of special securing devices or of special tools.

Referring to the attached drawings, Fig. I is a perspective view of the lid component in inverted position of my improved vault.

Fig. II is a similar view of the bottom component with the metallic lining thereof lifted partly out to better show the details of its construction.

Fig. III is a cross-sectional view of the lid component turned upside down.

Fig. IV is a corresponding cross-sectional view of the bottom component; and,

Fig. V is an end elevation of the vault with the lid component in place on the bottom component, a corner of the organization having been broken away and shown in section to illustrate how a hermetical seal is formed between the two components in accordance with the present improvement.

As delineated in these illustrations, my novel burial vault comprises a main or bottom component 10 of rectangular box-like configuration, and a lid component 11, both constructed from concrete or the like. The main or bottom component 10 of the vault is provided with an inner surfacing or lining 12 of non-corroding sheet metal, for example, copper, said lining being preferably separately made in the form of an insert with soldered or welded corner joints. As shown in Figs. II and IV, the lining 12 has a lateral flange 13 that extends over the top edge of the bottom component 10. It will further be noted that marginal portions of the flange 13 are downturned, as at 14, to slightly over-

lap the outside wall surfaces of the bottom component 10, said flange being formed at intervals with openings 15. Before assembling, I apply to the insides and to the top edges of the bottom component 10, a layer 55 of a bonding agent such as molten tar or pitch, and then insert the lining 12 under sufficient pressure to insure compacting of the bonding agent 12' into the form of a continuous homogeneous film. Attendant upon 60 this operation it will be apparent that some of the bonding agent will ooze up through the openings 15 in the flange 13 of the lining 12, with resultant formation of "keys" which effectively assist in the retainment of said 65 lining within the component 10.

The lid component 11 is of solid concrete construction, and has, in its under face, a continuous perimetric recession 16 formed jointly through marginally reducing the thickness, 70 and by a band 17 of stout metal inset around its perimeter. Like the bottom component 10, the lid component 11 is provided with a lining 18 of non-corroding sheet metal which 75 covers its entire under surface including the recess 16. Here again, the lining 18 is preferably preformed and secured by interposition of a bonding agent 19. It is important to note that the lining 18 is turned up at the edges into the form of a flange 20, which, 80 in practice, is soldered or welded fast to the metallic band 17; and, in addition, said lining is provided within the recess 16 with a series of key openings 21 to correspond with the openings 15 in the flange 13 of the lining 85 12 in the bottom component 10 of the vault.

In the use of the vault, the bottom component 10 is placed in the open grave in preparation to receive the burial casket, and the lid placed alongside the grave and its perimetric 90 recess 16 is filled with a slow hardening cementitious plastic, as shown at 22 in Fig. III. After lowering of the casket into the bottom component 10 incident to interment, the lid component 11 is placed, right side up, 95 upon said component section 10, as shown in Fig. V, wherefrom it will be seen that the depression 16 of the lid component 11 engages over the top edge of the bottom component 10. Due to the weight of the lid component 100

11, the plastic cement 22 is compressed and oozes out from the juncture both interiorly and exteriorly of the vault, with formation of sealing welts all around, as indicated at 5 23, 24 in Fig. V.

From the foregoing it will be seen that through my invention it is possible to fasten the lid component 11 of the vault in absolute liquid and gas tight relation to the main or 10 box component 10 of the vault without the aid of special securing means or of special tools, so that the interred body is protected against extraneous influences over an indefinite period of time, the juncture being 15 made positively efficient through complete mergence of the various bonding agents 12', 19 employed in the structure by way of the key openings 15, 21 in the metallic linings 12 and 18. In other words, the burial vault of 20 my invention has all the advantages inherent to concrete, as regards strength and permanency, combined with the hermetic tightness of the sheet metal; both the concrete and the metal being effectively sealed along the plane 25 of juncture between the lid and bottom components 11, 10 by the cementitious bonding material previously applied to the perimetric recess in said lid component. The described method of sealing moreover greatly facilitates 30 interment and obviates undue prolongation of the ceremony.

Having thus described my invention, I claim:

1. A burial vault of masonry comprising a 35 box-like bottom component with a lining of non-corroding sheet metal having a flange to extend over the top edge of the bottom component and secured by an interposed film of cementitious bonding material, said flange 40 being perforated for penetration by the bonding agent with attendant formation of retaining keys; and a lid component having a perimetric recess in its under face adapted to be filled with a slow-hardening cementitious plastic and to engage over the top edge of the bottom component, with formation 45 of a hermetical seal all around when the lid component is placed in position on the bottom component incident to interment, 50 said lid component being also provided with a lining of non-corroding sheet metal having key openings along the bottom of the perimetric recesses aforementioned.

2. A burial vault of masonry comprising a 55 box-like bottom component with a lining of non-corroding sheet metal having a flange to extend over the top edge of the bottom component and secured by an interposed film of cementitious bonding material, said flange 60 being perforated for penetration by the bonding agent with attendant formation of retaining keys; and a lid component with a perimetric recess in its under face adapted to be filled with a slow-hardening cementitious plastic and to engage over the top edge of 65

the bottom component, with formation of a hermetical seal all around when the lid component is placed in position on the bottom component incident to interment, said lid component being also provided with a lining of non-corroding sheet metal having openings in the flange of the lining of the bottom component. 70

3. In a burial vault the combination of a box-like bottom component with a lining of 75 non-corroding sheet metal lapping the upper marginal edge, a similarly sheathed cover having a perimetric recess in its underface to engage over said marginal edge, and openings in the engageable metal faces affording key ways for reception of suitable bonding agent whereby the cover is effectively interlocking sealed to the box-like component. 80

4. In a burial vault the combination of a box-like bottom component with a lining of 85 non-corroding sheet metal lapping and exteriorly surrounding the upper marginal edge thereof, a similarly sheathed cover having a preformed perimetric flange reinforced by surrounding metal band with provision of 90 a continuous recess in its underface to engage over the marginal edge aforesaid, and openings in the engaging metal faces affording key ways for reception of a suitable bonding agent whereby the cover is effectively interlocking sealed to the box-like component. 95

In testimony whereof, I have hereunto signed my name at Philadelphia, Pennsylvania, this 29th day of March, 1930.

RICHARD D. COGSWELL.
